No 1,000

S. B. Jerome's
Design for Clock Case Fronts.

Patented May 1, 1858.

Fig. 1.

Fig. 2.

Des. 1000

Samuel B. Jerome, of Waterbury, Conn.
Letters Patent No. 1000, dated May 4th 1858.

The schedule referred to in these Letters Patent and making part of the same.

To all whom it may concern:—

Be it known that I, Samuel B. Jerome, of Waterbury, in the County of New Haven, and State of Connecticut, have invented a design for clock case fronts, the construction and operation of which, I have described in the following specification & illustrated in the accompanying drawings, with sufficient clearness to enable competent and skillful workmen in the arts to which it pertains, or is most nearly allied, to make and use my invention.

In the accompanying drawings.

Fig. 1, is a front elevation of my design.

Fig. 2, is a section which shows the mode of putting the parts together.

A, is a wooden rim which forms the outer portion of the

front of the case of a marine time piece in which the glass B. in front of the dial is secured. An ornamentally designed piece of metal matting C. is placed immediately behind this glass, and secured in position by pieces of wood placed behind, very much in the manner in which looking-glasses are fastened in their place in the frame.

I claim the combination of the octagonal rim A with the metal matting C. in the formation of a design for clock case fronts as described and shown.
